(57) **CLAIM**

The ornamental design for a beverage container, as shown
and described.

DESCRIPTION

FIG. 1 is a top perspective view of a first embodiment of a
beverage container showing our new design;

FIG. 2 is a bottom perspective view thereof.

FIG. 3 is a front elevational view thereof.

FIG. 4 is a right side elevational view thereof.

FIG. 5 is a left side elevational view thereof.

FIG. 6 is a rear elevational view thereof.

FIG. 7 is a top plan view thereof.

FIG. 8 is a bottom plan view thereof.

FIG. 9 is a top perspective view of a second embodiment
thereof.

FIG. 10 is a bottom perspective view thereof.

FIG. 11 is a front elevational view thereof.

FIG. 12 is a right side elevational view thereof.

FIG. 13 is a left side elevational view thereof.

FIG. 14 is a rear elevational view thereof.

FIG. 15 is a top plan view thereof.

FIG. 16 is a bottom plan view thereof.

FIG. 17 is a top perspective view of a third embodiment
thereof.

FIG. 18 is a bottom perspective view thereof.

FIG. 19 is a front elevational view thereof.

FIG. 20 is a right side elevational view thereof.

FIG. 21 is a left side elevational view thereof.

FIG. 22 is a rear elevational view thereof.

FIG. 23 is a top plan view thereof.

FIG. 24 is a bottom plan view thereof.

FIG. 25 is a top perspective view of a fourth embodiment
thereof.

FIG. 26 is a bottom perspective view thereof.

FIG. 27 is a front elevational view thereof.

FIG. 28 is a right side elevational view thereof.

FIG. 29 is a left side elevational view thereof.

FIG. 30 is a rear elevational view thereof.

FIG. 31 is a top plan view thereof.

FIG. 32 is a bottom plan view thereof.

(Continued)

FIG. 33 is a top perspective view of a fifth embodiment thereof;
FIG. 34 is a bottom perspective view thereof;
FIG. 35 is a front elevational view thereof;
FIG. 36 is a right side elevational view thereof;
FIG. 37 is a left side elevational view thereof;
FIG. 38 is a rear elevational view thereof;
FIG. 39 is a top plan view thereof;
FIG. 40 is a bottom plan view thereof;
FIG. 41 is a top perspective view of a sixth embodiment thereof;
FIG. 42 is a bottom perspective view thereof;
FIG. 43 is a front elevational view thereof;
FIG. 44 is a right side elevational view thereof;
FIG. 45 is a left side elevational view thereof;
FIG. 46 is a rear elevational view thereof;
FIG. 47 is a top plan view thereof;
FIG. 48 is a bottom plan view thereof;
FIG. 49 is a top perspective view of a seventh embodiment thereof;
FIG. 50 is a bottom perspective view thereof;
FIG. 51 is a front elevational view thereof;
FIG. 52 is a right side elevational view thereof;
FIG. 53 is a left side elevational view thereof;
FIG. 54 is a rear elevational view thereof;
FIG. 55 is a top plan view thereof;
FIG. 56 is a bottom plan view thereof;
FIG. 57 is a top perspective view of an eighth embodiment thereof;
FIG. 58 is a bottom perspective view thereof;
FIG. 59 is a front elevational view thereof;
FIG. 60 is a right side elevational view thereof;
FIG. 61 is a left side elevational view thereof;
FIG. 62 is a rear elevational view thereof;
FIG. 63 is a top plan view thereof; and,

FIG. 64 is a bottom plan view thereof.
The broken lines in the drawings depict portions of the beverage container that form no part of the claimed design.
